 The National Cash Register Company, Dayton,
 Ohio, a corporation of Maryland

Application August 25, 1941, Serial No. 408,157

8 Claims. (Cl. 86—47)

The present invention relates to a mechanically operated device for loading the magazines of repeating firearms.

The present invention is directed to a mechanically operated device to feed cartridges into the magazines of repeating firearms until said magazines are filled to capacity. In the present embodiment of this device, the cartridges are fed one at a time from a storage hopper or clip into a spring-actuated magazine which, after being filled, is used to feed the cartridges into the firing chamber of an automatic repeating firearm. The present invention eliminates the hand-loading of such magazines, which at best is a tedious and slow process, and especially is this true when the cartridges to be loaded are of a comparatively large caliber and the magazines associated therewith are of heavy and/or rugged construction. The present machine is constructed to handle these large-caliber cartridges efficiently.

With the above statements in mind, it is broadly an object of this invention to provide a mechanically operated device for loading cartridges into the magazines of repeating firearms.

Another object of this invention is the provision of a mechanically operated device for transferring comparatively large-caliber cartridges, one at a time, from a storage hopper or clip into the magazine of a repeating firearm.

With these and incidental objects in view, the invention includes certain novel features of construction and combinations of parts, the essential elements of which are set forth in appended claims, and a preferred form or embodiment of which is hereinafter described with reference to the drawings which accompany and form a part of this specification.

In said drawings:

Fig. 1 is a side elevation of the complete device, partially sectioned to illustrate certain details better, showing a loading clip and a magazine in place on said device.

Fig. 2 is a detail view of a fragment of the spiral spring for actuating the feeding mechanism of the magazine.

Fig. 3 is a detail view, partially sectioned, of the magazine spindle for transmitting the power of the magazine spring to the cartridge-feeding mechanism of said magazine.

Fig. 4 is a detail sectional view taken along line 4—4 (Fig. 3), looking in the direction indicated by the arrows, showing specifically the ratchet teeth and clutch tenons for clutching the magazine spring to the feeding mechanism.

Fig. 5 is a sectional view taken along line 5—5

(Fig. 1), looking in the direction of the arrows, showing in detail the slide for advancing the cartridges into the spiral groove of the magazine after said cartridges have been fed from the clip into the mouth of said magazine.

Fig. 6 is a sectional view taken along line 6—6 (Fig. 1), looking in the direction of the arrows, showing the detail construction of the magazine and the slide for advancing cartridges into the spiral groove of said magazine.

Fig. 7 is a sectional view taken along line 7—7 (Fig. 1), looking in the direction indicated by the arrows, showing in detail the mechanism for feeding cartridges from the hopper or clip into the magazine.

Fig. 8 is a sectional view showing in detail the retaining fingers for the cartridge clip.

Fig. 9 is a sectional view taken along line 9—9 (Fig. 1), looking in the direction of the arrows, and shows in particular the construction of the feed bar mechanism.

Fig. 10 is a sectional view taken along line 10—10 (Fig. 1), looking in the direction indicated by the arrows, showing in particular the operating crank and associated mechanism.

Fig. 11 is a top plan view of the complete device with the cartridge hopper or clip removed.

Fig. 12 is a detail perspective view of the ratchet lever for tensioning the spring for the cartridge feeding mechanism.

Fig. 13 is a plan view of the bed portion of the device of this invention.

Fig. 14 is a sectional view of the bed taken along line 14—14 (Fig. 13), looking in the direction indicated by the arrows, showing the shape of the portion of the cartridge slot or channel located directly beneath the cartridge magazine.

Fig. 15 is a detail perspective view of the slide bar for feeding cartridges from the clip to the magazine.

Description

As previously explained, the present invention is directed to a comparatively simple and extremely efficient device which upon the operation of a hand crank unloads firearm cartridges from a clip or hopper and simultaneously loads them into the spiral groove of a drum type magazine for automatic repeating firearms.

Directing attention to Figs. 1, 11, and 13, the mechanism of the device of the present invention is supported on a bed plate or table 25 having secured to each end thereof standards or legs 26 and 27 which support said table 25 at the proper height for convenient operation. The plate or

table 25 has running lengthwise therein an inclined T-shaped slot or channel 28, which slidably supports a cartridge feed slide or bar 29 (see also Figs. 7, 9, and 15), which bar is retained in said slot 28 by rails 30 and 31, which also assist in slidably supporting said bar 29. The rails 30 and 31 (Fig. 7) are secured in a portion of the slot 28.

A downward extension 32 of the bar 29 (Figs. 1 and 9) has a hub portion 33 having therein a boring which forms a bearing for a pin 34, which pin in turn forms a pivotal support for the left-hand ends of two identical links 35 and 36. The right-hand ends of the links 35 and 36 (Figs. 1 and 10) are pivoted on a screw stud 37 secured in similar crank arms 38 and 39 having secured thereto, respectively, a trunnion stud 40 and a short shaft 41, both of which are journaled in borings in similar downward extensions of a bracket 42 secured to the table 25. Secured to the right-hand end of the short shaft 41 (Figs. 1 and 10) is an operating crank 43 having a handle 44, by means of which said crank, the shaft 41, and the arms 38 and 39 are manually rotated. A bushing 45 (Fig. 10) free on the stud 37 maintains the proper spacing between the links 35 and 36.

As presently constructed, the device of this invention is arranged for manual operation. However, it is considered but a matter of mechanical skill to arrange the device for mechanical operation by connecting the shaft 41 to some power source, such as an electric motor, through the use of pulleys and a belt or other suitable means.

Operating the crank 43 (Figs. 1 and 10) causes the slide or bar 29 to slide back and forth in the inclined slot 28, for a purpose presently to be described.

Referring still to Figs. 1, 11, and 13, the table 25 has therein a rectangular opening 46, which communicates with the slot 28, said opening adapted to receive the mouth of a clip 47, which holds sufficient cartridges 48 to fill the spiral cartridge track or groove in the cartridge magazine. The clip 47 has secured to the mouth thereof of a band 49, which is adapted to engage a shoulder in the opening 46 and is locked in place against said shoulder by two eccentric clamps 50 and 51, which may be brought into engaging relationship with said band 49 after the clip 47 is properly placed in said opening 46, after which the eccentric clamps 50 and 51 may be rotated to lock said clip 47 in place. The eccentric clamps 50 and 51 are rotatably supported in holes in brackets 52 and 53 secured to the top surface of the table 25, and each of said clamps 50 and 51 is provided with a cross pin to facilitate the turning thereof.

The clip 47 (Figs. 1 and 8) has opposed spring fingers 54 near the mouth thereof to prevent the cartridges 48 from rolling out of said clip 47 when it is in a substantially horizontal position. However, the tension of the spring fingers 54 is not sufficient to prevent said cartridges 48 from dropping into the slot 28 when the feeding bar 29 is retracted.

In Fig. 1, the feed bar 29 is shown in fed position. Turning the hand crank 43 in a counter-clockwise direction causes the crank arms 38 and 39, in cooperation with the companion links 35 and 36, to shift the bar 29 toward the left until the face of a fiber plug 55 pressed in a hole in the righthand end of said bar, moves beyond the nose or bullet end of the bottom cartridge 48 in the clip 47. This permits the cartridges 48 to shift down-

wardly, under their own weight, to bring the bottom cartridge into the inclined groove or channel 28, where said cartridge comes to rest on a V-shaped track or way formed by the rails 30 and 31 (Fig. 7). It will be noted that the nose of the bullet of the bottom cartridge 48 comes to rest on a conforming curved surface of an extending lip 142 formed on the end of the feed bar 29. Continued rotation of the hand crank 43 causes the feed bar 29 to reverse its movement and shift toward the right, whereupon the face of the fiber plug 55 engages the nose of the bottom cartridge 48, which now rests on the track formed by the rails 30 and 31, to feed said cartridge toward the right, out of register with the clip 47 and into the mouth of a magazine 56.

The mouth of the magazine 56 is adapted to fit into a rectangular depression 57 (Figs. 1, 11, and 13) in the top surface of the table 25, which depression connects with the channel 28 for guiding the cartridges 48 from the clip 47 into the mouth of said magazine 56. The mouth of the magazine 56 (Figs. 1, 6, and 11) is retained in the depression 57, and said magazine is retained in proper position on the table 25, by means of studs 58 and 59 on the left-hand end of said magazine, which studs slip under a rounded nose 60 formed on the bracket 53, and by means of a lip 61 on said magazine, which rests on an upper surface of an extension of a bracket 62 secured to the top surface of the table 25, and said lip is clamped against said surface by a slide bolt 63, which is adapted to pass thereover. The slide bolt 63 fits freely in a slot in the bracket 62, and said bolt has therein a slot adapted to be engaged by a rounded extension on a handle 64 pivoted on a pin in an upward extension of said bracket 62.

To remove the magazine 56 from the table 25, the handle 64 is moved upwardly to shift the bolt 63 toward the right (Fig. 1) out of engagement with the lip 61. Said magazine may then be grasped by convenient handles 65 and 66 and tilted toward the left until the right-hand end of the mouth of said magazine clears the table 25, after which said magazine may be shifted toward the right to move the studs 58 and 59 from beneath the rounded nose 60. The magazine may then be lifted clear of the table 25. The reverse procedure is followed in putting a new magazine in place on the table 25.

The construction of the mouth of the magazine 56 (Fig. 1) is such that it is open for the insertion and removal of cartridges only on the left-hand side of said magazine, or the side adjacent to the clip 47, and the construction of said mouth is such that it is necessary to feed the cartridges into and out of said mouth lengthwise and one at a time. The mouth of the magazine 56 (Figs. 1 and 6) has inturned lips 67 to hold the cartridges 48 against downward movement and to insure that they are fed into and out of said mouth in the manner explained above.

While the slide bar 29 (Fig. 1) is traveling toward the right to feed the bottom cartridge 48 out of the clip 47 and into the magazine 56, the top surface of said bar passes beneath the next cartridge in said clip to obstruct downward movement of all the cartridges 48 until said slide bar 29 is returned to its starting position.

It will be noted by referring to Fig. 1, that the feed bar 29 is of sufficient length that the top surface thereof substantially covers the opening or mouth of the clip 47 when said bar 29 is in fed position. This prevents the possibility of the lefthand end of the feed bar 29 nibbling on the

nose of the bottom cartridge 48 when said bar is being returned toward the left from fed position, as shown, to initial or take-up position.

After a cartridge 48 (Fig. 1) has been fed into the mouth of the magazine 56, as explained above, a lifter mechanism functions to raise the cartridge into the spiral groove of said magazine and to hold said cartridge in such raised position until another cartridge is fed therebeneath.

The cartridge lifter mechanism includes a slide 70 (Figs. 1, 5, and 6) mounted for substantially vertical shifting movement by means of tongues on opposite edges thereof in cooperation with corresponding grooves in downwardly extending posts 71 and 72 secured to the bottom surface of the table 25. The slide 70 carries a stud 73, which forms an axle for rollers 74 and 75 arranged to cooperate, respectively, with camming surfaces 76 and 77 on the upper edges of the links 35 and 36.

Continued counter-clockwise rotation of the hand crank 43 (Fig. 1), after a cartridge 48 has been fed into the mouth of the magazine 56, returns the links 35 and 36 and the feed bar 29 toward the left, causing the camming surfaces 76 and 77 on said links 35 and 36, in cooperation with the rollers 74 and 75, to lift the lifter slide 70 through an opening in the table 25 until a shoulder 78 on one edge of said slide moves above a latching tooth 79 on a rod 80. The right-hand end of the rod 80 slides in a boring in the post 71, while the left-hand end of said rod is pivoted on a pin 81 secured in a downwardly-extending arm of a three-armed lever 82 pivoted on a stud 83 (Figs. 1, 7, and 9) supported by upturned extensions of similar brackets 84 and 85 secured to the bottom surface of the table 25.

A spring 143 (Fig. 1) tensioned between the pin 81 and the post 71, urges the lever 82 counter-clockwise and the rod 80 toward the right to normally maintain the tooth 79 in engagement with the left-hand edge of the slide 70, as here shown. Therefore, when the shoulder 78 moves above the tooth 79, as explained above, the spring 143 immediately moves said tooth 79 beneath said shoulder 78 to latch the slide 70 in its upward position. In addition to the spring 143, a rounded nose 86 (Figs. 1 and 9) on the left-hand arm of the lever 82 is engaged by the hub 33, near the end of return movement toward the left of the bar 29, to rock said lever 82 counter-clockwise to shift the rod 80 toward the right to insure that the tooth 79 moves beneath the shoulder 78, in case said spring 143 for any reason fails to effect such movement.

The instant the right-hand end of the bar 29 moves beyond the left-hand end of the lowest cartridge in the clip 47, said cartridge drops down into the channel 28, whereupon continued rotation of the crank 43 causes the links 35 and 36 to shift the bar 29 toward the right to feed said cartridge into the mouth of the magazine 56 and beneath the lowest cartridge in said magazine, which cartridge is held by the lifter slide 70 and the latch rod 80 in a position above the cartridge now being fed. After the cartridge now being fed is beneath the left-hand end of the bottom-most cartridge in the magazine 56, the hub 33 on the feed bar 29 (Figs. 1 and 9) engages a rounded nose 87 on the right-hand arm of the lever 82 to rock said lever clockwise to shift the rod 80 toward the left to disengage the tooth 79 from the shoulder 78. This releases the slide 70, which drops downwardly, due to gravity, until a shoulder 69 on said slide engages a stop stud 69 in the post 72, in

which position the slide is out of the path of the incoming cartridge. However, in addition to the operation of the slide 70 due to gravity, positively-actuated means is provided to insure that the slide 70 is moved down out of the path of the incoming cartridge. This positively-actuated mechanism includes a lever 88 (Figs. 1, 5, 6, and 7), the left-hand end of which is pivoted on the stud 83, while the right-hand end of said lever is pivoted on a stud 89 in the slide 70. The lever 88 is slotted at its right-hand end, as shown in Fig. 5, to clear the post 71 and the slide 70, and is also slotted at its left-hand end, as shown in Figs. 1 and 7 to clear the lever 82.

While the hub 33 (Figs. 1 and 9) continues in engagement with the nose 87, to prevent the spring 143 from returning the tooth 79 into engagement with the shoulder 78, said hub 33 engages a rounded camming surface 90 on the top edge of the lever 88 to rock said lever clockwise to shift the lifter slide 70 downwardly out of the path of the incoming cartridge 48. The hub 33 (Fig. 1), in cooperation with the top edge of the lever 88, holds said lever and the lifter slide 70 against upward movement, while a cartridge is being fed into the magazine 56. The slot formed by the upward extensions of the side members of the brackets 84 and 85 (Figs. 1 and 7) provides clearance for the left-hand end of the links 35 and 36, while the arms 38 and 39 (Fig. 10) provide clearance for the right-hand ends of said links.

If for any reason forward or feeding movement of the feed bar 29 (Fig. 1) is interrupted before the hub 33, in cooperation with the camming surface 90, forces the lifter slide 70 downward, momentum of the comparatively heavy cartridge 48 may be sufficient to cause the ignition end of said cartridge to strike the upper left-hand corner of said lifter slide 70 with sufficient force to discharge said cartridge. To overcome this condition, the upper left-hand corner of the slide 70 has been tapered, as indicated by the reference numeral 144, so that only the extreme rim of the cartridge being fed will strike said block, thereby overcoming the danger of said cartridge being discharged. A rubber bumper 145 (Fig. 1) inserted in a hole in the right-hand wall of the opening 57 and located opposite the mouth of the magazine 56, provides a cushion against which the incoming cartridge 48 strikes, to further overcome the danger of said cartridge being accidentally discharged.

From the foregoing description, it is evident that turning the crank 43 counter-clockwise (Fig. 1) causes the cartridges 48 to be fed one at a time, and in a continuous stream, from the clip 47 into the magazine 56, and that, as the cartridges 48 (Figs. 1 and 6) are fed into the mouth of the magazine 56, they are lifted upwardly by the lifter mechanism into a spiral groove 91 formed by similar spiral strips 92 and 93 secured, respectively, to the right-hand and left-hand side plates 94 and 95 of said magazine 56. A curved cover plate properly spaces the side plates 94 and 95 and is clamped between said side plates by bolts extending therebetween.

As the cartridges 48 are pushed upwardly into the spiral groove 91, they follow said groove until the magazine is filled to capacity, and this is determined by the cartridge feeding mechanism coming into contact with a stop stud 96 (Fig. 6) projecting from the left magazine side plate 95.

A tension device, which is effective when the 75 loaded magazine is attached to a firearm, is pro-

vided for feeding the cartridges constantly into the mouth of the magazine, from which position they are fed into the firearm, and, as this tension device also plays an important part in the loading of the magazine 56, a brief description thereof will now be given.

The tension device for feeding the cartridges 48 out of the magazine 56 and into the firearm comprises a hollow spindle or shaft 97 (Figs. 1, 3, and 6) journaled in borings in the center of the side plates 94 and 95 and having secured thereto a casting 98. The casting 98 and the shaft 97 have registering slots adapted to slidably receive a bar 99 carrying a stud 100, to which is pivoted the upper end of a link 101. A stud 102 pivotally connects the lower end of the link 101 to another link 103 pivotally connected by a stud 104 to a cartridge feed bar 105 (Figs. 1 and 6) having a rounded surface 106 adapted to resiliently engage the first cartridge 48 in the spiral groove 91, as shown in Fig. 6. The feed bar 105 carries a stud 107, which forms an axle for a roller 108, while the studs 100 and 102, respectively, rotatably support rollers 109 and 110. The rollers 108, 109, and 110 are arranged to roll freely in the spiral groove 91 formed by the spiral strip 92, to guide the feed bar 105 in said groove. The links 101 and 103 form a flexible connection between the bar 99 and the feed bar 105, so that said feed bar may readily follow the spiral groove. The matching slots in the shaft 97 and the casting 98 (Fig. 6) permit the bar 99 to move in and out as the rollers 108, 109, and 110 travel around the spiral groove 91.

Tension is applied to the shaft 97 (Fig. 6), the casting 98, the bar 99, and the feed bar 105 by a flat spiral spring 111, which is similar to a heavy clock spring and which urges said parts, including the cartridge feed bar 105, in a counter-clockwise direction, as viewed in Fig. 6, to constantly urge the cartridges 48 toward the mouth of the magazine 56. The flat spring 111 is connected to the shaft 97 and associated parts in the following manner:

Free on the shaft 97 (Figs. 1, 2, and 3) is a sleeve 112 having two lugs 113, which engage corresponding slots in the internal end of the spring 111, while the external end of said spring is connected by rivets 114 (Fig. 6) to the inside surface of a drum 115 secured to the left-hand plate 95, said drum forming a housing for said spring 111.

The left-hand end of the sleeve 112 (Figs. 3 and 4) has a plurality of combined ratchet and clutch teeth 116 adapted to cooperate with similar teeth in the right-hand end of a clutch sleeve 117 slidably supported on the hollow shaft 97 and having therein four clutch slots adapted to engage four corresponding clutch tenons 118 formed on the periphery of the shaft 97. A compressible spring 119 (Fig. 3) fits loosely around a reduced portion of the left-hand end of the shaft 97 and is compressed between a shoulder in the sleeve 117 and a pin 120 in the left-hand end of the shaft 97 to urge said sleeve 117 toward the right or inwardly to normally maintain the teeth therein in engagement with the corresponding teeth 116 on the end of the sleeve 112. However, the clutch teeth in the sleeve 117 may be disengaged from the corresponding clutch teeth 116 and retained disengaged by pulling outwardly or toward the left on said sleeve, against the action of the spring 119, until the clutch cuts in said sleeve are free of the tenons 118, after which revolving said sleeve 117 a slight distance will move

the clutch cuts out of alignment with the tenons 118 and permit a shoulder formed in the boring of said sleeve to come to rest on the ends of said tenons 118, to retain the teeth on said sleeve 117 out of engagement with the teeth 116.

When the magazine 56 (Fig. 1) is being loaded, the sleeve 117 is separated from the sleeve 112, as here shown. Consequently, the spring 111 is not tensioned and remains so until the magazine is completely loaded. After the magazine 56 has been loaded to capacity, a wrench 121 (Fig. 12) is used for tensioning or winding the spring 111.

The handle portion of the wrench 121 rotatably supports a bushing 122 having on the periphery thereof ratchet teeth 123, which cooperate with a spring-pushed ratchet pawl 124 pivoted on a screw stud secured in said handle 121. The bushing 122 has, in the boring thereof, diametrically opposed slots 125 adapted to engage corresponding tenons 126 (Figs. 1, 3, and 11) on the sleeve 112, for the purpose of revolving said sleeve to tension the spring 111 after the magazine has been filled with cartridges.

After the spiral groove 91 (Fig. 6) in the magazine 56 has been filled with cartridges, which is determined by the roller 109 striking the stop stud 96, said magazine is removed from the table 25 and placed with the right plate 94 down, so that the sleeve 117 extends upwardly. Next, the sleeve 117 is revolved in either direction by hand until the four clutch cuts thereon engage the tenons 118 on the shaft 97 and the teeth on said sleeve 117 engage the teeth 116 on the sleeve 112. Next, the wrench 121 is slipped over the sleeve 117, and the slots 125 in the bushing 122 are engaged with the tenons 126. Working the handle of the wrench 121 back and forth causes the ratchet pawl 124, in cooperation with the teeth 123 on the bushing 122, to rotate said bushing and the sleeve 112 in a clockwise direction, as viewed in Fig. 6, to tension or wind the spring 111. The teeth 116 on the sleeve 112 ratchet over the teeth on the sleeve 117, which latter teeth are spring-urged into engagement therewith and which, together with the shaft 97 and the sleeve 117, are retained stationary by the cartridges 48 and the stud 96 when the magazine is filled to capacity.

An indicating device, not shown, is connected to the sleeve 112 to indicate when the spring 111 is properly and/or fully tensioned.

Tensioning the spring 111 as explained above causes the sleeve 112, due to its connection to the sleeve 117, to urge said sleeve, the shaft 97 (Fig. 6), the casting 98, the bar 99, and the cartridge feed bar 105 counterclockwise to constantly urge the cartridges 48 toward the mouth of the magazine, so that, as fast as one cartridge is moved out of said mouth into the firearm, another cartridge will immediately take its place, to cause said firearm to fire automatically as long as there are any cartridges in the magazine 56.

Before an empty magazine 56 is placed on the table 25 (Figs. 1 and 6) for refilling, the teeth in the sleeve 117 are disengaged from the teeth 116 in the sleeve 112, as shown in Figs. 1 and 3 and as explained before, to disconnect the shaft 97 from the sleeve 112, so that the lifter mechanism will not have to function against the tension of the spring 111 as the cartridges 48 are fed around the groove 91. However, it has been found necessary to apply sufficient friction to the shaft 97 and connected parts to hold the cartridges 48 against the action of gravity as they are fed around the declining portions of the spiral groove

91. If no tension is applied to the shaft 97 and connected parts, the cartridges 48 may run ahead of the lifter mechanism when they reach the declining portions of the spiral groove 91, and, as a result, they may become wedged in said groove and thus interfere with the proper loading of the magazine 56.

Means for imparting the proper restraint to the shaft 97 and connected parts, including the cartridge feed bar 105 (Figs. 1 and 6), comprises a friction disk 130 (Figs. 1, 9, and 11) free in a boring in a plate 131 hinged to the bracket 53. Secured in the center of the disk 130 is a stud 132, the tenon of which extends into a boring in the plate 131 to assist in rotatably supporting said disk 130. The disk 130 has in the periphery thereof an annular groove engaged by friction studs 134 and 135 free in diametrically opposed holes in the plate 131 and maintained in frictional engagement with the bottom of the groove 133 by compressible springs 136 and 137, the tension of which springs may be adjusted by screws 138 and 139 threaded in the holes for said springs and said studs. The hinged connection between the bracket 53 and the plate 131 permits said plate and the friction mechanism to be swung out of the way while the magazines 56 are being removed from and placed on the table 25. A pin 140 (Fig. 9) free in a hole in the plate 131 is arranged to be engaged with a hole in an upward extension of the bracket 53 to hold the plate 131 and the friction mechanism in operating position, as shown in Fig. 1.

As stated above, the pin 140 is disengaged from the hole in the extension of the bracket 53, and the plate 131 and the friction mechanism are swung toward the left, as viewed in Fig. 1, out of the way, until a new magazine is mounted on the table 25. After the new magazine is in place, the plate 131 is swung back toward the right, and the tapered nose of the stud 132 is simultaneously engaged with the borings in the sleeve 117 and the hollow shaft 97, after which the disk 130 is rotated, by means of the knurled periphery thereof, until a slot 141 in the stud 132 engages the pin 120 (Fig. 3) secured in the left-hand end of the hollow shaft 97. After the slot 141 in the stud 132 has been engaged with the pin 120, the securing pin 140 is engaged with the hole in the upward extension of the bracket 53 to hold the plate 131 and the friction mechanism carried thereby in operating position, as shown in Fig. 1. This connects the friction mechanism to the shaft 97 (Figs. 1 and 6), the casting 98, and the cartridge feed mechanism, including the bar 99, the links 101 and 103, and the cartridge feed bar 105, and said friction mechanism imparts sufficient restraint to the above parts to maintain the rounded surface 106 on the feed bar 105 in constant engagement with the first cartridge 48. This maintains the cartridges in close formation or in constant contact with each other as they are fed around the spiral groove 91, thereby overcoming the danger of any of the cartridges becoming wedged in said spiral groove while moving around the declining side thereof.

After the magazine 56 has been loaded with cartridges, the pin 140 (Figs. 1 and 9) is withdrawn from the hole in the upward extension of the bracket 53, and the plate 131 and the friction mechanism are swung toward the left, as viewed in Fig. 1, to permit the removal of the loaded magazine from the table 25. After the loaded magazine has been removed from the table 25, the sleeve 117 is revolved by hand (Figs.

1 and 3) until the ratchet teeth therein engage the teeth 116 in the sleeve 112, after which the spring 111 (Figs. 2 and 6), which operates the cartridge feeding mechanism, is tensioned by means of the wrench 121 (Fig. 12) in the manner explained earlier herein.

While the form of mechanism shown and described herein is admirably adapted to fulfill the objects primarily stated, it is to be understood that it is not intended to confine the invention to the one form or embodiment herein disclosed, for it is susceptible of embodiment in various forms, all coming within the scope of the claims which follow.

15. What is claimed is:

1. In a device of the class described, in combination with a magazine for feeding cartridges into a repeating firearm and a container for holding cartridges to be transferred to the magazine, of a stand comprising a table portion to support the magazine and the container; means including a reciprocating member carried by the table for transferring the cartridges, one at a time, from the container to a point opposite the magazine; a lifting device for lifting each cartridge from the table into the magazine; means to maintain the lifting device in elevated position to support the cartridges in elevated position until the next fed cartridge has been moved partially under the elevated cartridges; and means to thereafter release the lifting device.

2. In a device for transferring cartridges from a container to a magazine for repeating firearms, the combination of a stand including a table portion and supports therefor; depressions in the table for receiving the container and the magazine; means to removably clamp the container and the magazine in the depressions; an inclined channel in the table to connect the depressions and to form a passageway for the cartridges; a reciprocating member operable in the channel to advance cartridges from the container to the magazine; a lifting device operable in conjunction with the member to lift the last advanced cartridge into the magazine; means to maintain the lifting device in elevated position to support the last advanced cartridge in lifted position until the next advanced cartridge has moved partially therebeneath; and a means to release the lifting device after said last advanced cartridge has moved partially beneath the last lifted cartridge.

3. In a device for transferring cartridges from a container to a magazine for repeating firearms, the combination of a stand including a table portion and supports therefor; openings in the table for receiving the container and the magazine; means to removably clamp the container and the magazine in the openings; an inclined channel in the table to connect the openings and to form a passageway for the cartridges; a slide mounted in the channel; means to reciprocate the slide to advance the cartridges one at a time from the container into the magazine; a lifting device operable by the reciprocating means to lift the last advanced cartridge out of the path of movement of the next advancing cartridge; means operable by the slide to retain the lifting device in lifted position until said next advancing cartridge has started beneath said lifted cartridge, whereupon the slide releases said retaining means; and means operable by the slide to force the lifting device downwardly out of the path of said next advancing cartridge.

4. In a device of the class described for trans-

ferring cartridges from a container to a magazine for repeating firearms, the combination of a stand including a table portion and supports therefor; two openings in the table adapted to receive, respectively, the container and the magazine; means to clamp the container and the magazine in the openings; an inclined channel in the table connecting the two openings; a slide mounted in the channel; means to actuate the slide; means to connect the slide to the actuating means so that operation of said actuating means will reciprocate said slide to feed the cartridges, one at a time, from the container, through the channel and into the magazine; means operated by the connecting means to lift the last fed cartridge out of the path of movement of the next fed cartridge; means operated by the slide to latch the lifting means in lifted position until the next fed cartridge has moved partially beneath the last fed cartridge, after which said slide releases the latching means; and means operated by the slide to force the lifting means downwardly out of the path of the incoming cartridge.

5. In a device of the class described for transferring cartridges from a container to a magazine for repeating firearms, the combination of a stand including a table portion and supports therefor; two openings in the table to receive, respectively, the container and the magazine; means to clamp the container and the magazine in the openings; an inclined channel connecting the two openings; a slide mounted in the channel; means to operate the slide; links to connect the operating means to the slide to cause said operating means to impart a feeding and a take-up movement to said slide to feed the cartridges, one at a time, from the container, through the channel, and thence into the magazine; means to lift the last fed cartridge out of the path of movement of the next fed cartridge; rollers on the lifting means; camming surfaces on the links cooperating with the rollers, during take-up movement of the slide, to lift the lifting means; means operated by the slide during its take-up movement to latch the lifting means in lifted position until the next fed cartridge has started beneath the last fed cartridge, whereupon said slide, during its feeding movement, unlatches said latching means; and means operated by the slide, during its feeding movement, to force the lifting means downwardly out of the path of the incoming cartridge.

6. In a device of the class described for transferring firearm cartridges from a container to a magazine for repeating firearms, said magazine having a mouth for the insertion and removal of cartridges and a follower or feeding mechanism normally effective to urge the cartridges toward the mouth but adapted to be rendered ineffective to so urge said cartridges when the magazine is being filled, the combination of a stand comprising a table portion and supports therefor; two openings in the table for the insertion, respectively, of the container and the magazine; separate means to clamp the container and the magazine in their respective openings; a channel in the table connecting the two openings and forming a passageway for the cartridges; a slide mounted in the channel; means to reciprocate the slide in advancing and take-up directions to advance the cartridges, one at a time, from the container into the mouth of the magazine; means operated by the reciprocating means to lift the last advanced cartridge into the magazine and out of the path of the next advanced cartridge; means rendered effective by the slide during its

take-up movement to latch the lifting means in lifting position, said latching means adapted to be rendered ineffective by the slide during its feeding movement and after the next advanced cartridge has started beneath the last advanced cartridge; means operated by the slide and effective after the latch has been rendered ineffective to force the lifting means downwardly out of the path of the next advanced cartridge; and a friction device cooperating with the cartridge follower or feeding mechanism to yieldingly retain said follower mechanism in contact with the cartridges to prevent misalignment and sticking of said cartridges as they are fed into the magazine.

15. 7. In a device of the class described for transferring firearm cartridges from a container to a magazine for repeating firearms, said magazine having a mouth for the insertion and removal of cartridges and a follower or feeding mechanism normally effective to urge said cartridges toward the mouth but adapted to be rendered ineffective to so urge said cartridges when the magazine is being filled, the combination of a stand comprising a table portion and supports therefor; two openings in the table for the insertion, respectively, of the container and the magazine; separate means to clamp the container and the magazine in their respective openings; a channel in the table connecting the two openings and forming a passageway for the cartridges as they are fed from the container to the magazine; a reciprocating slide mounted in the channel and adapted to feed the cartridges from the container into the magazine; a lifting device operable in conjunction with the slide to lift the last fed cartridge out of the path of movement of the next fed cartridge; and a friction device connectible to the cartridge follower mechanism and operable in conjunction therewith to apply sufficient resistance to the cartridges as they are fed into the magazine to hold said cartridges in close formation so that they will not become misaligned and interfere with the proper loading of said magazine.

20. 8. In a device of the class described for transferring cartridges from a container to a magazine for repeating firearms, said magazine having a mouth for the insertion and removal of cartridges and a follower or feeding mechanism normally effective to urge the cartridges toward the mouth but adapted to be rendered ineffective to so urge said cartridges when the magazine is being filled, the combination of a stand comprising a table portion and supports therefor; two openings in the table to receive, respectively, the container and the magazine; separate means to clamp the container and the magazine in their respective openings; an inclined channel connecting the openings and forming a passageway for the cartridges; a slide reciprocably mounted in the channel; a crank to operate the slide; links to connect the crank to the slide so that operation of said crank will reciprocate said slide in feeding and return directions to feed the cartridges, one at a time, from the container into the mouth of the magazine; a block slidably mounted on the table and adapted to lift the last fed cartridge out of the path of movement of the incoming cartridge and into the magazine proper so that the incoming cartridge may move into the mouth of the magazine; rollers on the block; camming surfaces on the links adapted to cooperate with the rollers, during return movement of the slide, to raise the block to lift the

cartridges; a projection on the slide; means operated by the projection, during return movement of the slide, to latch the block in raised position until the incoming cartridge has moved partially beneath the last fed cartridge, after which said projection, during feeding movement of the slide, unlatches said latching means; means operated by the projection, during feeding movement of the slide, to force the block downwardly out of the path of the incoming car- 10

tridge; a friction device connectible to the cartridge follower mechanism and operable in conjunction therewith to cause said follower mechanism to apply sufficient resistance to the cartridges as they are fed into the magazine to hold said cartridges in close formation so that they will not become misaligned and interfere with the proper loading of said magazine.

ROBERT M. WHITMORE.
